(57) **CLAIM**

The ornamental design for a vending machine, as shown and described.

DESCRIPTION

FIG. 1 is a front view of a vending machine, showing our new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a top-right-front perspective view thereof.

FIG. 8 is a bottom-left-front perspective view thereof.

FIG. 9 is a bottom-left-rear perspective view thereof; and, FIG. 10 is a top-right-rear perspective view thereof.

The broken line showing of protrusions (e.g., "legs" or "feet") on the bottom of the vending machine, the broken line showing of a mostly circular logo within the large circle on the front of the vending machine, and the broken line showing of a mostly circular logo within the large circle on the rear of the vending machine are for the purpose of illustrating environmental structure and form no part of the claimed design.
